UNITED STATES PATENT OFFICE.

MASASHI TANIKAWA, OF NEW YORK, N. Y.

MOVING-PICTURE TOY.

1,151,977.

Specification of Letters Patent. Patented Aug. 31, 1915.

Application filed April 16, 1915. Serial No. 21,807.

To all whom it may concern:

Be it known that I, MASASHI TANIKAWA, a subject of the Mikado of Japan, residing in the borough of Brooklyn, New York city, in the county of Kings and State of New York, have invented certain new and useful Improvements in Moving-Picture Toys, of which the following is a specification.

My invention relates to moving picture toys and my object is the production of a simple, cheap device for the amusement of children, which will produce the illusion of a moving picture, when viewed on a screen.

In the drawing Figure 1 is a view, partly in section, of the device and Fig. 2 a like view taken at right angles to the first.

The toy comprises a box 1 having a front 2 carrying a lens 3, a mirror 4 extends at an angle of 45° from the front bottom edge to 20 the top rear edge and reflects the image formed by the lens to a ground glass screen 5 forming the top of the box. A hood 6 protects the ground glass from the direct light rays and may be folded down over 25 the ground glass to protect it when not in use.

To produce the illusion of moving pictures a rotary disk 7 is mounted adjacent to the lens with the alternate cut-out parts 8 and solid parts 9. This disk is preferably perforated at the edge 11. A second disk 11 is mounted at the side of the box 12, at right angles to the first and is provided with teeth 11 which engage the perforations at 35 10 on the disk 7. A handle 13 on the disk 11 projects through the side of the box and on rotating the handle the disk 11 revolves, rotating the disk 7 with it, causing the light beams passing through the lens to be interrupted, thereby causing the peculiar flickering image of a moving picture of any objects toward which the toy may be pointed to appear on the ground glass screen. The disk 7 may be weighted at 14 so that the

lens will be covered unless the handle is 45 rotated. To further heighten the illusion a light spring 15 bears against the teeth 11 so that when the latter is rotated, a clicking, moving picture machine sound will be produced. 50

I claim—

1. In a toy, a box, a lens in the front thereof, a mirror therein, on which the image is formed, a viewing screen thereover to receive the image, an apertured disk adjacent to the lens and means for rotating said disk. 55

2. In a toy, a box, a lens in the front thereof, a mirror therein on which the image is formed, a viewing screen thereover to receive the image, an apertured disk adjacent to the lens provided with apertures near its edge; a second disk at right angles to the first, projections on the edge of the second disk engaging the perforations on 65 the first and a handle for revolving the second disk.

3. In a toy, a box, a lens in the front thereof, a mirror therein on which the image is formed, a viewing screen thereover, 70 an apertured disk adjacent to the lens, means for rotating the disk and a device for simulating the clicking sound of a moving picture machine.

4. In a toy, a box, a lens in the front 75 thereof, a mirror therein on which the image is formed, a viewing screen thereover, an apertured disk adjacent to the lens weighted on one side to cause it to cover the lens when stationary, and means for rotating the disk. 80

In testimony whereof I have affixed my signature in presence of two witnesses.

MASASHI TANIKAWA.
